GAME TABLE

Hans P. Luhn, New York, N. Y.

Application February 8, 1932. Serial No. 591,592

9 Claims. (Cl. 273—136)

This invention relates to apparatus for playing games which require playing surfaces of distinctive design. More particularly the invention provides a game board or table equipped with means for selectively varying the playing surface thereof whereby a plurality of different games may be played alternatively on the same board.

A number of the games in common use for recreation today are closely related with respect to operational characteristics and necessary equipment. This class of games involves the movement of markers in a prescribed manner upon a playing surface having a distinctive design or pattern; and the essential difference in the play lies in the design of the playing surface and the manner of marker movement thereon. Checkers and backgammon are two familiar examples of the class of games to which the present invention pertains.

It has been customary heretofore to provide a separate board or table for each individual game of this type. When it is desired to have available facilities for playing any one of a number of such games, a corresponding number of boards or tables are required. This involves considerable inconvenience and expense, which it is an object of the present invention to eliminate by providing a game board or table having a selectively variable playing surface.

According to the present invention a game board or table top is constructed with a rectangularly shaped central opening adapted to receive a vertically movable board disposed therebeneath. A selected game design carried on a playing surface of flexible material is placed upon said board in register with said opening. An upward movement of the said movable board serves to press the playing surface against the opening in the table top and to provide firm support for the same during the play of the selected game. Each game design may be on a separate piece of flexible material, the selected game design being placed manually upon the board, or, in the preferred embodiment of my invention, an extended playing surface of flexible material carrying a plurality of different game designs in succession thereon may be arranged to pass over the said movable board. In the latter case, means are provided for moving the extended playing surface across the opening to bring the selected game design into register therewith. In either case, it will be seen that by my invention one game board or table may be used alternatively

in the play of a plurality of different games requiring playing surfaces of distinctive design.

As will appear more fully hereinafter, it is immaterial in the exercise of the present invention whether the apparatus takes the form of a board or a table, the essential elements being the same in either embodiment. It is contemplated that the preferred commercial embodiment will be the table form having folding legs similar to the ordinary card table, and the drawings forming a part of this specification accordingly illustrate the invention in this form. It is to be clearly understood, however, that the invention is not intended to be limited in this respect.

In the accompanying drawings, in which like reference characters denote like parts:

Figure I is a plan view of a game table constructed according to the invention, with the operating mechanism on the under side of the table indicated in dotted lines;

Figure II is an end view of the table shown in Figure I;

Figure III is a longitudinal section along the line 3—3 in Figure I;

Figure IV is a longitudinal section along the line 4—4 in Figure I, showing the board 26 moved upwardly into playing position;

Figure V is a section along the line 4—4 in Figure I, showing the board 26 moved down to permit lateral movement of the playing surface;

Figure VI is a transverse section along the line 6—6 in Figure I, showing in detail the construction and assembly of one of the playing surface rollers;

Figure VII is a transverse section along the line 7—7 in Figure I, showing in detail the mounting of the shaft 32; and

Figure VIII is an enlarged detail view of the eccentric mounting of the shaft.

Referring now to the drawings, 10 is a table top having an opening 12 centrally spaced therein. Longitudinal braces 14 located adjacent the sides of the opening 12 are secured to the under side of the table top 10 and carry brackets 16 adapted to receive the ends of rollers 18 and 20 transversely disposed beneath the table top adjacent the respective ends of the opening 12 therein. The rollers are rotatable in the brackets 16 and are provided with knobs 22 at the ends thereof to facilitate turning the same.

An extended playing surface 24 of flexible material, having designs for a plurality of different games in successive arrangement thereon, is carried by the rollers 18 and 20. One end of

said playing surface is permanently attached to one of said rollers; while the other end of said playing surface may be either permanently or removably attached to the other of said rollers, 5 as described hereinafter. The playing surface, unwinding from one of the rollers, passes beneath the table top 10 across the opening 12, and winds upon the other roller so that a portion of the said surface is always visible from above 10 through the opening 12. In the view of the apparatus shown in Figure I, the playing surface is in a mid-way position showing parts of two game designs, neither of which is in register with the opening. During actual use, of course, 15 the playing surface should be in such position that the desired game design is in register with the opening.

A vertically movable board 26 is located beneath the opening 12 in the table top 10 and 20 beneath the playing surface 24 extending across said opening. The board 26 is adapted to enter and substantially close the opening 12 with the section of the playing surface in register therewith and provides firm support for the same during 25 the play of a selected game. In the embodiment illustrated in the accompanying drawings, the edges of the table top 10 adjacent the opening 12 therein and the edges of the board 26 are oppositely chamfered to facilitate movement of 30 the board into and out of said opening and to prevent movement of the playing surface 24 during play by gripping the playing surface between said chamfers, as shown in Figures IV and VII.

The board 26 is provided with spaced longitudinal braces 28 secured to the under side thereof and carrying brackets 30 intermediate the ends thereof. The brackets 30 are adapted to receive a shaft 32 rotatable therein and arranged to support and move said board. The shaft 32 is eccentrically mounted in cylindrical bearings 34, 40 fixedly attached to said shaft adjacent the respective ends thereof. Brackets 36, secured to the brace rods 14 of the table top 10 and aligned with the brackets 30 depending from the board 26, have circular openings therein to receive and provide bearing surfaces for the bearings 34 of the shaft 32. The said shaft thus is supported by and turns in the brackets 30; and in turn 45 supports the board 26 and occasions vertical movement thereof in either direction by reason of the eccentric mounting of the said shaft. Handles 38 to facilitate turning the shaft 32 may be formed by bending the ends thereof through 50 ninety degrees.

The table top 10 may conveniently be provided with supporting members of conventional type, as for example folding legs 40 in the manner of the familiar folding card table. Referring particularly to Figure I in the drawings, it will be noted that the opening 12 in the table top 10 as well as the operating mechanism of the apparatus is spaced in from the outer edges of the said top 55 for a sufficient distance to avoid discomfort to players seated at the table by contact therewith.

When it is desired to use the apparatus, the board 26 is lowered by turning the shaft 32 until the eccentric mounting acts to cause a downward movement thereof. The rollers 18 and 20 are then turned to move the playing surface 24 across the opening 12 in the table top 10. When a desired game design has been brought into register with the opening 12, the lateral movement 70 of the playing surface is stopped. The shaft 32 is then turned, until the eccentric mounting 75

thereof elevates the board to a position within the opening 12 as demonstrated in Figure IV of the accompanying drawings. In this position, the playing surface 24 is gripped between the edges of the board 26 and the edges of the table top 10 adjacent the opening 12 and is thus held from further lateral movement. The beveled contact between the board and the table top assists the eccentric mounting of the shaft 32 in holding the former rigid and level; and the board 26 therefore provides firm support for the section of the playing surface 24 utilized for the play of the selected game.

My apparatus may also readily be adapted to the play of card games and for like purposes. This may be accomplished by having an end of the extended playing surface 24 removably attached to one roller, as described above. The extended playing surface 24 is disconnected from the roller to which it is removably attached and wound completely upon the other roller. The board 26 is then moved upwardly into the opening 12, making it flush with the top of the table, and the apparatus is ready for use as a card table, tea table, or the like, as desired. It will be desirable for this use of the table to have the upper surface of the board 26 finished to harmonize with that of the table top 10. An alternative way of accomplishing this result is to provide a blank space on the extended playing surface 24, which, 100 preferably, matches the surrounding surface of the table. It will then not be necessary to have the playing surface 24 removably attached to one of the rollers. When it is desired to use the apparatus for playing cards or the like, the blank 105 space referred to may simply be moved into register with the opening 12 and the board raised as described, thus providing a substantially uniform playing surface.

The specific description so far given relates 110 chiefly to the embodiment of my invention in which an extended playing surface is employed. Where it is desired to have each game design on a separate piece of flexible material, the apparatus remains the same except that the rollers 18 115 and 20 and their supports and knobs may be eliminated. To use this modification of my invention the movable board 26 is lowered as described above, the selected game design manually placed upon the board in register with the opening, 120 and the board raised into position, closing the opening 12. The piece of flexible material on which the game design is carried is made slightly larger than the opening 12, and will thus 125 be clamped between the chamfered edges of the opening 12 and the board 26, as shown in the drawings.

If desired, a drawer or drawers may be arranged beneath the table top 10, thereby providing space in which to store game counters for 130 the various games to be played, and, in the modification of my invention employing separate playing surfaces, the playing surfaces not in use.

I claim:

1. Apparatus for games requiring playing surfaces of distinctive design, which comprises a table top having an opening therein, a vertically movable board disposed beneath said opening, said board being adapted to enter and substantially close said opening, means for moving said board vertically in either direction, and a playing surface of flexible material adapted to be gripped between the edges of said opening and said board when said board is raised.

2. Apparatus for games requiring playing sur-

- faces of distinctive design, which comprises a table top having a substantially rectangular opening centrally spaced therein, a vertically movable board disposed beneath said opening, 5 said board being adapted to enter and substantially close said opening, means for moving said board vertically in either direction, and a playing surface of flexible material carrying a game design thereon and adapted to be gripped between the edges of said opening and said board when said board is raised, with its game design 10 in register with said opening.
3. Apparatus for games requiring playing surfaces of distinctive design, which comprises a table top having a substantially rectangular chamfered opening centrally spaced therein, a vertically movable chamfered board disposed beneath said opening, said board being adapted to enter and substantially close said opening, means 15 for moving said board vertically in either direction, and a playing surface of flexible material carrying a game design thereon and adapted to be gripped between the chamfered edges of said opening and said board when said board is raised, 20 with its game design in register with said opening.
4. Apparatus for games requiring playing surfaces of distinctive design, which comprises a table top having a substantially rectangular chamfered opening centrally spaced therein, a vertically movable chamfered board disposed beneath said opening, said board being adapted to enter and substantially close said opening, means 25 for moving said board vertically in either direction, said means comprising an eccentrically mounted shaft rotatably secured to the under side of said table top and to the under side of said board, and a playing surface of flexible material carrying a game design thereon and adapted to 30 be gripped between the chamfered edges of said opening and said board when said board is raised, with its game design in register with said opening.
5. Apparatus for games requiring playing surfaces of distinctive design, which comprises a table top having an opening centrally spaced therein, an extended playing surface of flexible material having designs for a plurality of different games in successive arrangement thereon, means for moving said playing surface beneath said top across said opening to bring selected game designs alternatively into register therewith, a vertically movable board disposed beneath said opening and beneath said playing surface, 55 and means for moving said board vertically in either direction.
6. Apparatus for games requiring playing surfaces of distinctive design, which comprises a table top having an opening centrally spaced therein, an extended playing surface of flexible material having designs for a plurality of different games in successive arrangement thereon, means for moving said playing surface beneath 60
- said top across said opening to bring selected game designs alternatively into register therewith, a vertically movable board disposed beneath said opening and beneath said playing surface, said board having substantially the same shape and peripheral dimension as said opening, and means for moving said board vertically in either direction. 80
7. Apparatus for games requiring playing surfaces of distinctive design, which comprises a table top having a chamfered opening centrally spaced therein, an extended playing surface of flexible material having designs for a plurality of different games in successive arrangement thereon, means for supporting said playing surface on the under side of said table top, means for moving said playing surface beneath said top across said opening to bring selected game designs alternatively into register therewith, a vertically movable chamfered board disposed beneath said opening and beneath said playing surface, said board being adapted to enter and substantially close said opening, and means for moving said board vertically in either direction. 85
8. An apparatus for games requiring playing surfaces of distinctive design, which comprises a table top having a substantially rectangular chamfered opening centrally spaced therein, an extended playing surface of flexible material having designs for a plurality of different games in successive arrangement thereon, rollers rotatably secured to the under side of said table top adjacent the two ends of said opening, the ends of said playing surface being attached respectively each to one of said rollers, a vertically movable chamfered board disposed beneath said opening and beneath said playing surface, said board being adapted to enter and substantially close said opening, and an eccentrically mounted shaft rotatably secured to the under side of said table top and to the under side of said board. 90
9. Apparatus for games requiring playing surfaces of distinctive design, which comprises a table top having a substantially rectangular chamfered opening centrally spaced therein, an extended playing surface of flexible material having designs for a plurality of different games in successive arrangement thereon, rollers rotatably secured to the under side of said table top adjacent the two ends of said opening, one end of said playing surface being permanently attached to one of said rollers and the other end of said playing surface being removably attached to the other of said rollers, a vertically movable chamfered board disposed beneath said opening and beneath said playing surface, said board being adapted to enter and substantially close said opening, and an eccentrically mounted shaft rotatably secured to the under side of said table top and to the under side of said board. 105

HANS P. LUHN.
